UNITED STATES PATENT OFFICE.

NATHAN KOHLER, OF BROOKLYN, NEW YORK.

DESIGN FOR A GAME-BOARD.

SPECIFICATION forming part of Design No. 17,915, dated November 29, 1887.

Application filed October 21, 1887. Serial No. 253,047. Term of patent 7 years.

To all whom it may concern:

Be it known that I, NATHAN KOHLER, residing at Brooklyn, county of Kings, State of New York, have invented and produced a new 5 and original Design for a Game-Board, of which the following is a specification, reference being had to the accompanying drawing, forming part thereof, and which represents a face view of my newly-designed game-board.

10 The leading feature of my design consists in the representation of a checker-board with triangular projections and with a double row of circles around it that extend through the squares of the checker-board and through the 15 triangles.

A is the checker-board, having the heavy central line, a. At opposite sides of board A are the triangles b, these triangles having sides which are dark where they traverse light 2c squares and light where they traverse dark squares.

c are circles arranged in two rows that constitute a margin. d is an inner marginal line, and e are short lines at right angles to the line d and dividing circles c. The circles c extend through the squares of the checker-board and through the triangles. The corners f of the checker-board contain diagonally-located circles f'. 25

What I claim is—

30 The design for a game-board, consisting of checker-board A, triangles b, circles c, line d, and transverse line e, the corners f of the checker-board having circles f', substantially as shown.

NATHAN KOHLER.
